UNITED STATES PATENT OFFICE.

PIERRE GUILLAUMIN, OF VOIRON, FRANCE.

WEIGHING-MACHINE.

SPECIFICATION forming part of Letters Patent No. 400,400, dated March 26, 1889.

Application filed January 9, 1888. Serial No. 260,248. (No model.) Patented in France May 2, 1881, and September 19, 1887, No. 185,930; in England May 6, 1887, No. 6,686; in Belgium September 9, 1887, No. 78,827; in Luxembourg September 9, 1887, No. 890; in Italy September 10, 1887, No. 22,244; in Germany September 16, 1887, No. 43,850; in Austria-Hungary September 21, 1887, No. 37,049 and No. 66,089, and in Russia October 3, 1887, No. 8,760.

To all whom it may concern:

Be it known that I, PIERRE GUILLAUMIN, a citizen of the Republic of France, residing at Voiron, in said Republic, have invented a new and useful Improvement in Weigh-Bridges and Weighing-Machines, (for which a patent was granted to me in the said Republic of France May 2, 1881, No. 185,930, and also dated September 19, 1887; in Great Britain, No. 6,686, dated May 6, 1887; in Belgium, No. 78,827, dated September 9, 1887; in Germany, No. 43,850, dated September 16, 1887; in Italy, No. 22,244, dated September 10, 1887; in Luxembourg, No. 890, dated September 9, 1887; in Austria-Hungary, No. 37,049 and No. 66,089, dated September 21, 1887, and in Russia, No. 8,760, dated October 3, 1887,) of which the following is a specification.

Heretofore, in order properly to graduate the beams of scales for weighing heavy things so that they would be accurate, either expensive and complicated machinery was required or sufficient weights or weighted material to prove each separate graduation. In fact, no scale could be warranted accurate without such test-weights.

The object of my invention is to produce a scale which shall be capable of verifying its own weight by the use of fractional parts of that weight, substantially as hereinafter specified; and the nature of the invention consists in the details of combination and construction, substantially as illustrated in the drawings, hereinafter described, and subsequently pointed out in the claim.

Figure 1 is a side view in elevation illustrating the registering part of my improved weighing-bridge and the top of the platform on which the material to be weighed is deposited. Fig. 2 is a plan view illustrating the levers which sustain the platform. Figs. 3 and 4 are detail views illustrating the stand on which the registering-beams are mounted.

Upon the stand M are mounted in proper bearings the two scale-beams I I and K K, one above the other, as illustrated. The platform-lever C is attached to the lower beam, K K, at A by the link, and the rod o, which is attached to said lever C at o'. The platform

P' is mounted on the ordinary triangular lever, L l, and adapted to receive the articles to be weighed. The fulcrum of the beam K K is near the link A A. At A' is hung a counterpoise, S. The upper beam, I I, is fulcrumed at I' in the upright arm of the stand, and projecting without the upright arm is connected by the jointed link B' to the lower beam, K K. On the lower beam are two P's or movable weights, Q and q. On the upper beam is only one P or movable weight, Q'.

The space designated by the dotted line F is divided into two parts, one designated by the dotted line T, the other by the dotted line t. The space t is graduated to represent units of the system of weights for which the scale was built. In the example given it is for kilograms. The space T is graduated for a fractional part of the unit of weight. In the example given it is one one-hundredth of the kilogram. The space upon the upper beam (indicated by the dotted line T') is graduated for a smaller fraction of the unit of weight than the space T of the lower beam. In the example given this graduation is for thousandths of a kilogram. Upon the beam K K over the space T moves the P Q and over the space t moves the P q. Upon the beam I I over the space T' moves the P Q'. Upon the beam K K both lines of graduations are numbered from the outside end of the beam toward the fulcrum; but the graduations of the upper beam are numbered in the usual way from the fulcrum outward. Upon the link B' is hung a receptacle, B, in which are to be placed the detached weights, (designated by V of Fig. 3,) which represent various sums of the unit of weight, the whole weighing apparatus to be substantially as illustrated in the drawings.

To use this weighing apparatus, the article to be weighed is deposited on the platform P', as usual. Then within the receptacle B is placed one or more of the detached weights before described until the end of the beam K K comes down in the usual way. Then the operator, by summing the amounts represented by the weights V in B, will have an indication of the weight of the article on the platform. To

prove this, and be sure that it is accurate, the operator (while the article is still on the platform and V in B) moves first the $P\ q$ along the graduations t until he finds the graduation 5 which will balance the scale. If the scale be correct, that graduation should indicate an amount equal to the sum of the weights V. If, however, he cannot balance the scale with the $P\ q$, he must have recourse to the $P\ Q$, 10 moving it on the graduation in the space T—an adjunct to determine the fractional parts of its denomination. If he can thus balance the scale with the two P 's Q and q , the indication given by the graduations will be in the example here given units and hundredths of an unit of the weight. If, however, the operator cannot accurately balance the scale with the two P 's Q and q , he must have recourse to the $P\ Q'$, 15 moving it on the upper beam, I I, until the scale balances. Then for the $P\ q$ the graduation in the example given will indicate the units of weight, the $P\ Q$ the hundredths of an unit of weight, and the $P\ Q'$ the thousandths of an unit of weight. If the sums of 20 the weights V and the sums of the indications on the beams be the same, the scale is correct 25

and accurate. If, however, there be a difference between these sums, then that difference is the variation of the scale.

It is obvious that any unit of weight and 30 any fractional parts thereof may be used instead of the example here given.

What I claim as my invention, and desire to secure by Letters Patent, is—

In a weighing apparatus, the combination 35 of the platform P', the levers L l, the connecting-lever C, the connecting-rod o, and the stand M, with the beams K K and I I, the counterpoise S, attached to said beam K K, the link A, attaching the beam K K and the 40 connecting-rod o, the jointed link B', connecting the two said beams and supporting the receptacle B, the P 's Q , q , and Q' , the graduations T, t , and T', and the weights V, substantially as and for the purpose set forth. 45

In witness whereof I hereunto set my hand in presence of two witnesses.

PIERRE GUILLAUMIN.
